(57) **CLAIM**

The ornamental design for an automotive wheel, as shown and described.

DESCRIPTION

FIG. 1 is a perspective view of an automotive wheel, showing my new design;

FIG. 2 is a front view thereof;

FIG. 3 is a perspective view of the automotive wheel of FIG. 1 with the center cap removed for illustrative clarity; and, FIG. 4 is a front view of FIG. 3.

The broken line showing of the wheel is included for the purpose of illustrating environment and forms no part of the claimed design.
